UNITED STATES PATENT OFFICE.

SELBY GOSSE, OF CAMBRIDGE, MASSACHUSETTS.

PROPELLING APPARATUS.

1,273,216.

Specification of Letters Patent. Patented July 23, 1918.

Application filed October 31, 1917. Serial No. 199,524.

To all whom it may concern:

Be it known that I, SELBY GOSSE, a British subject, residing at Cambridge, in the county of Middlesex and State of Massachusetts, have invented certain new and useful Improvements in Propelling Apparatus, of which the following is a specification.

This invention is a propelling apparatus more particularly adapted for marine propulsion wherein an endless belt is employed having thereon hingedly or pivotally mounted blades or paddles that may be operated to drive a boat, ship, or other marine vessel ahead or astern.

15 One object of the invention is to provide a propelling apparatus that may be employed to drive a ship, boat, or other marine vessel, ahead or astern through the agency of an endless belt having blades or paddles thereon.

20 Another object is to provide suitable tripping devices to engage with the belt for varying the position of the blades or paddles.

A further object is to provide suitable driving wheels for maintaining the belt in proper position and inclosing the belt and wheels in a closure so that a portion of the belt which is driving is exposed.

A still further object is to form an endless belt with links having pivotally mounted blades or paddles so that when the blades or paddles are inoperative they are adapted to lie in openings in the links, the alternate links having their blades so mounted as to swing in one direction while the other alternating blades are adapted to swing in the opposite direction.

One purpose of the invention is to provide an endless propelling belt having pivotally mounted blades or paddles that are actuated to their inoperative position by the interposition of suitable tripping devices and providing each of the blades or paddles with suitable anti-friction devices that will serve to maintain them in their operative position.

45 Broadly stated the invention comprises a closure having therein suitable driving wheels over which is adapted to travel an endless belt having pivotally mounted blades or paddles in the links thereof, and 50 providing means for moving certain of the blades or paddles to an inoperative position, while permitting the others to be placed in their operative positions, each of the blade

positions being determined by the direction of travel of the belt.

55 One practical form of construction and assembly will be described and illustrated in the accompanying drawings, in which:—

Figure 1 is a side elevation partly in section,

60 Fig. 2 is a transverse sectional view of the hull of a vessel with the driving mechanism in position.

Fig. 3 is a perspective view of one of the links and its blade or paddle, and showing 65 the blade in position in the opening in the link,

Fig. 4 is a perspective view showing the 70 other type of link and blade, with the blade in its operative position, and

Fig. 5 is a bottom plan view of two links with their blades in an inoperative position.

In the preferred embodiment about to be described the hull of a vessel is generally indicated at A. In the construction shown 75 in Fig. 2 two driving or propelling mechanisms are employed and in Fig. 1 a vertical section is shown through a portion of one of them. To suitably inclose the belt and its driving wheels a closure generally indicated at B may be employed. As shown the ends of this closure are rounded and suitable bearings are provided for the shafts 10 and 11. As shown the driving wheels 12 and 13 are preferably mounted in suitable recesses 80 85 which generally conform to the periphery of the wheels.

The wheels as shown are hexagonal and are provided with suitable teeth indicated at 90 14 which project outwardly from the periphery. The portion of the periphery adjacent the teeth may be formed as an additional side so that the periphery, when strictly speaking, is composed of 12 sides. These driving wheels 12 and 13 are spaced apart 95 and secured upon the shafts 10 and 11 and in order to complete the closure B between them a section having two curved sides is employed as indicated at C. The curved sides are adapted to lie adjacent the wheels 100 and connecting two ends of the curves is a flat section indicated at 15. Oppositely positioned is another flat side indicated at 16 that is provided with the shoulder portions indicated at 17 and 18.

105 Adapted to coöperate with the driving

wheels 12 and 13 is a belt which may be generally indicated at D. This belt is preferably endless and is composed of several kinds of links, two of which are indicated 5 in Figs. 3 and 4. These links may be formed of any suitable material and of such size and shape as will best perform the functions required of them. The link shown in Fig. 3 is preferably formed of a flat plate 10 19 and may be provided with the openings 20 formed adjacent the corners of said plate. The plate may be substantially rectangular as shown and at a convenient point, intermediate of its length, it may be provided 15 with suitable bearings indicated at 21. These bearings are preferably spaced apart and positioned transversely of the plate 19. To coöperate with the bearings 21, a pin 22 is employed which serves to effect a pivotal 20 mounting for the paddle or blade 23.

The paddle or blade 23, as shown, is circular in outline and has projecting therefrom at an angle a lug 24 which has two spaced arms indicated at 25 and 26, extending 25 therefrom. A notched portion is thereby formed between the arms 25 and 26 and adjacent the ends of the arms they are provided with suitable means for engaging with the shaft of a roller or any other anti-friction 30 device indicated at 27. The plate 19 is preferably formed longitudinally with a suitable rectangular opening 28 that is adapted to connect with a circular opening 29. As shown in Fig. 3 the blade or 35 paddle 23 is adapted to loosely lie within the recess or opening 29. The recess 28 is adapted to permit the roller 27, carried by the lug 24, to pass therethrough.

In Fig. 4 there is illustrated a different 40 type of link and this link consists of a flat plate 30. This plate 30 is provided with suitable slots 31 formed in the respective corners so that the type of link shown in Fig. 3 may be connected to the link shown 45 in Fig. 4. One means of connecting these two links is indicated by the loops 32. Any usual or efficient type of fastening may be employed that will give sufficient flexibility to the joint formed therebetween.

50 The plate 30 is provided with a circular recess 33 that is displaced slightly in the longitudinal direction. The recess 33 communicates with a substantially square recess 34 that extends toward one end of the plate 30. Adjacent the juncture of the recesses 33 and 34 the plate 30 is provided with suitable bearings 35 that are adapted to receive a pin or other cylindrical member. The pin is adapted to pass through a 55 suitable opening or hole in the paddle or blade 36.

The blade or paddle 36 is preferably circular in outline so that it may be received within the recess 33. The pin that 60 is adapted to be engaged with the bearings

35 preferably passes tangentially. Extending from the blade 36 is a lug 37 which may be slotted at its outer end and be provided with holes adjacent the end to form bearings for a roller or other antifriction 70 device 38. The blade 36 is provided with a rectangular slot 39 that extends from adjacent the pin holding the blade in the bearing 35 to a little more than one-half the diameter of the blade. 75

The pin in the bearings 35 in coöperation with a blade 36 provides for a pivotal movement of the blade 36. In order to limit the movement of the blade 36 in one direction the blade 36 is provided with a lug 40 which has a hole therethrough. A pin 41 is adapted to pass through said hole and be received and held therein. The pin projects sufficiently beyond the edges of the blade 36 so as to contact with the plate 30 85 adjacent the recess 33. The pin 41 will thus serve as a stop to prevent the blade 36 from passing through the recess.

The plate 30 is provided adjacent one end with a rectangular slot 42 which is preferably positioned between two of the end slots 31 and adjacent the recess 34. The portion of the slot forming the outer wall as indicated at 43 may be rounded to serve as a bearing for the eye end 44 formed on the 95 end of the limiting rod or arm 45. The outer end of the arm 45 is provided transversely with projections 46. 90

The arm 45 is thus rotatably mounted upon the rounded portion 43 and its straight portion is adapted to pass through the slot 39 formed in the blade 36. The projections 46 are adapted to engage with one surface of the blade 36. The arm 45 may be slightly bent as indicated at 47, and is shown more 100 particularly in Fig. 1. The arm 45 may also be provided with lugs 48 that are so positioned upon the sides of the arm that they will engage with the other surface of the blade 36. They will thus act as stop 110 members to limit the movement of the blade in the direction opposite to that limited by the pin 41.

The projections 46 will serve to guide the arm 45 in its movement through the slot 115 39. The paddles or blades 23 are preferably larger in diameter than the paddles or blades 36. As shown more particularly in Fig. 5, the blade or paddle 36 is adapted to swing and to move in a direction opposite to that of the blade or paddle 23. The blades or paddles 36, when in their extended or operative positions are adapted to propel the boat or other marine vessel in the forward direction and the blades or paddles 23 are adapted to propel the boat 120 astern or in the reverse direction.

The closure or casing B being adapted to receive the driving wheels 12 and 13 and the assembled belt, is provided with suitable 130

grooved portions that serve to accommodate the working portions used in the propulsion. In the sectional view shown in Fig. 2 the upper portion of the casing B is provided with a rectangular groove 49. At each end of this groove there is formed a smaller groove indicated at 50 and 51. The upper wall of this rectangular groove is also provided with a groove indicated at 52. The grooves 50 and 51 are adapted to receive the ends of the pins 41 as they pass therethrough and serve to maintain their respective blades or paddles 36 in an inoperative position. The rollers or anti-friction devices 38 are adapted to pass within the groove 52 and the assembled belt is adapted to pass through the groove 49. The portion of the closure that may be termed the bottom is formed with suitable grooves so that the belt D may travel in the proper direction so that the paddles or blades 23 and 36 will be adapted to engage with the water adjacent the keel section of the boat or other marine vessel.

The grooves which are formed in this lower portion closure are preferably in alignment with the ones formed at the top. Thus the groove 52 has a complementary groove 53 that communicates with the groove 54 that is complementary to the groove 49. The pins 41 are adapted to ride in the grooves 55 and 56 that are complementary to the grooves 50 and 51. Thus the belt will travel through grooves that are formed especially to accommodate the assembled belt D.

The section C of the closure is provided with the grooves 53, 54, and 56. At suitable points adjacent the lower grooved ends of this lower section C there are notched portions which may be generally indicated at 57 and 58. The notched portion 57 serves to accommodate a lever 59 which has a pivotal mounting at 60. The outer end of the lever 59 may be provided with a suitable roller or other anti-friction devices 61 that is adapted to contact with certain elements of the belt at predetermined times. To operate the lever 59 it is provided adjacent the pivotal connection 60 with an operating handle 62. The handle 62 preferably projects outside of the closure B. The connection 60 may be one that includes a shaft of such length that the roller 61 will be positioned to engage with the belt and at the same time permit the operating handle 62 to be placed at a convenient point outside of the closure.

The shouldered or notched portion 58 is adapted to receive a lever 63 which may have at its outer end a roller or other anti-friction device 64. The lever 63 is adapted to have a pivotal mounting as indicated at 65. This mounting may include a shaft that is adapted to be connected with an oper-

ating handle 66 positioned exteriorly of the closure B in a manner similar to that for the operating handle 62.

As shown in Fig. 1 the closure B is provided at its lower right hand semicircular end, and upon the interior diameter with a shouldered portion 67. This shouldered portion 67 provides a recess for receiving the lever 68, which lever is provided at its outer end with a roller or other anti-friction device 69. The lever 68 is pivotally mounted as indicated at 70. The pivotal mounting 70 may include a shaft that extends to the outside of the closure and may have attached thereto an operating lever 71.

Spaced from the line of travel of the blade or paddle 23 is a curved member 72 that serves as a guide. This curved member 72 is preferably mounted upon a shaft 73 which shaft is carried in a pedestal to other bearings supported at 74. The end of the shaft 73 is preferably connected in some suitable manner with a bell crank lever 75 as shown. The other end of the lever is connected with a push rod 76 that is adapted to pass through a suitable stuffing box 77 which as shown is connected with the boat A. The upper end of the rod 76 is provided with a head 78. A downward movement may be imparted to the rod 76 by means of the head 78 which in turn will be communicated to the bell crank lever 75 serving to move the shaft 73 and therefrom the curved guide member 72 into the path of travel of the blades or paddles 23. To more effectively produce this the bell crank lever may be pivotally mounted as indicated at 79.

In the bottom portion of the casing B where the groove 54 is adapted to contact with the water there is positioned at a convenient point a tongue 80. The tongue 80 is pivotally mounted as indicated at 81. The tongue 80 has connected to it an operating lever 82 having a handle end 83. The lever 82 may be connected to the tongue 80 at the point indicated at 84. The lever 82 serves to move the tongue into and out of its engagement with the angular end 85 formed just below the groove 55, and in the wall 86.

When the belt is driven so that its lower portion moves in the direction as indicated by the arrow the operating lever 82 is moved so that the tongue 80 moves up and forms a guide groove. The pins 41 in passing strike the angular end of the tongue, and are deflected downward which throws the blades or paddles 36 into the position indicated in Figs. 1 and 4. The antifriction devices 38 will then be caused to travel in the groove 53. The blade 36 in coming to this right angle position for driving purposes will cause the arm 45 to move upward through the slot 39 until the lugs 40 engage

with the blade and serve as a stop. The arm 45 will then press the blade against further backward movement on account of the eye end engaging with the link plate 30.

- 5 In order to provide for folding the blade or causing it to lie within the recess 33, the operating handle 62 is so moved that the lever 59 will bring its roller 61 into the path of travel of the roller 38. When the 10 roller 38 strikes the roller 61 it will throw the blade 36 upward into its respective recess at which time the arm 45 will move to the closed position. The blade when being folded is adapted to have its pin passed 15 through the guide slot indicated at 87. This guide slot may be so arranged that it may be closed entirely by means of the movable tongue 88 which may be carried for such movement in any suitable manner. In 20 order to move this tongue 88 it has connected to it a bell crank lever 89 that may be pivotally mounted to the closure as indicated at 90. The other end of the bell crank lever 89 may have connected to it a 25 push rod 91 having a handled end 92. As shown in Fig. 1 the guide slot 87 is angularly cut so that the two presenting ends of the closure and the tongue 87 are wedge shape.
- 30 When it is desired to reverse the direction of propulsion the shafts 10 and 11 are rotated in the opposite direction causing the wheels 12 and 13 and the belt D to move in the reverse direction. As the blades 36 35 carried in the links 30 are not adapted to propel in the opposite direction the links 19 are brought into play. In order that the blades or paddles 23 may be properly positioned the operating handle 71 is moved 40 which throws the lever 68 and its roller 69 so that the roller will engage with the roller 27. The roller 27 will then be thrown upward to engage with the groove 53 and will exert pressure in that direction.
- 45 This will tend to maintain the blade 23 at substantially right angles to the belt. The rod 82 is moved downward so as to close the guide slot by means of the tongue 80. This will present a smooth surface for 50 that portion of the groove. As the paddles 23 progress to the left, of Fig. 1, and it is desired to fold them, the operating lever 62 is moved so that the roller 61 is positioned out of the path of travel.
- 55 The operating rod 66 is moved so that the lever 63 will position its roller 64 to engage with the rollers 27. The position that the lever 63 and its roller will assume is indicated by the dotted lines. The striking of 60 the roller 27 against the roller 64 will tend to force the blade 23 upward into its folded position.

If during the operation certain of the blades or paddles 23 are projecting downward when it is desired to propel the boat

or vessel in the opposite direction the push rod 76 is operated to bring the curved guide member into play so that it will force the blades 23 to lie in their inoperative or folded position.

What I claim is:—

1. An endless belt which comprises a plurality of connected links, each link having pivotally mounted thereon a blade, said links being provided with openings that are 75 adapted to receive the blades when in their inoperative positions, and means to place alternate blades in a driving position and the remaining blades in their inoperative positions.

2. A propelling apparatus which comprises a closure, a belt formed of connected links, a plurality of driving and spacing wheels for the belt, the alternate links being provided with blades adapted to be received 85 within the links, the other links being provided with blades that are adapted to be received within the links, certain of the links having their blades extended when the belt is moved in one direction while the other 90 blades are carried within their respective links, means for causing alternate blades to be extended for propelling in one direction, means for causing the blades to be received within their respective links, means for moving 95 the other blades to their extending position for propelling in the opposite direction, and means for causing said latter blades to be received within their respective links.

3. A propelling apparatus which comprises a housing, a plurality of driving and spacing wheels mounted thereon, an endless belt formed of links provided with pivotally mounted blades and having anti-friction means serving to maintain the proper angularity of the blades, said housing being provided with grooves, and the walls of one of 100 said grooves being provided with movable members forming adjustable closures for 105 openings formed in one wall thereof to cooperate with the blades of the belt, in causing the blades to change from their operative and inoperative positions.

4. An endless belt, which comprises a plurality of plates connected together and serving as links, each of said plates being provided with openings and spaced bosses adjacent the openings, a blade pivotally mounted in the bosses and approximately closing the opening in the plate, and an arm extending 110 angularly from the blade at the pivot and provided at its outer end with a roller.

5. An endless belt, which comprises a plurality of plates connected together and serving as links, one of said plates having an opening therein and bosses adjacent the opening, a blade to approximately fill the opening and pivotally mounted on the plate and in the bosses, said blade being provided with a closed slot and transversely with a 115 120 125 130

boss, a pin projecting from the ends of the boss and beyond the sides of the plate, a rotatable arm secured at one end of each one of the plates and having its other end adapted to coöperate with and ride in the plate slot and also serving as a brace, an arm extending from the blade and oppositely thereto, and a roller carried by the outer end of said latter arm.

- 10 6. A propelling apparatus, which comprises a belt formed of connected plates constituting links, means for spacing and driving the belt, blades pivotally mounted on the plates and adapted to lie in openings formed 15 in the plates, manually operated trip means for causing certain and alternate blades to be moved to their operative driving and inoperative positions, said means including pivotally mounted levers adapted to engage

with the blades, and also including movable 20 tongues.

7. A propelling apparatus, which comprises a belt formed of connected plates having openings therein and constituting links, pivotally mounted blades carried by the 25 plates, means for operating said belt, a closure for the apparatus, said closure having its upper portion formed with longitudinal grooves for inclosing the belt and causing it to travel therethrough with the several 30 blades lying in their respective openings.

In testimony whereof I affix my signature in presence of two witnesses.

SELBY GOSSE.
